UNITED STATES PATENT OFFICE.

ULRICH KORNSTEIN, OF NEW YORK, N. Y.

CRUTCH.

1,288,929.

Specification of Letters Patent. Patented Dec. 24, 1918.

Application filed October 27, 1917. Serial No. 198,850.

To all whom it may concern:

Be it known that I, ULRICH KORNSTEIN, a citizen of the United States, and a resident of New York, in the county of New York 5 and State of New York, have invented certain new and useful Improvements in Crutches, of which the following is a specification.

The present invention relates to improvements in crutches, and has for its main object to provide a device of this kind which may be conveniently and quickly adjusted as to its length.

Another object of the invention is to produce a crutch the head of which may be adjusted angularly, so as to fit under the arm-pit of the user.

A further object of the invention is to produce a crutch that is yieldable under the 20 weight of the user, or in other words, one that is to some extent resilient, thereby obviating sudden shocks and jars to which the user would otherwise be subjected.

With these and other objects in view, 25 which will more fully appear as the nature of the invention is better understood, the same consists in the combination, arrangement, and construction of parts hereinafter described, pointed out in the appended claims 30 and illustrated in the accompanying drawings, it being understood that many changes may be made in the size and proportion of the several parts and details of construction within the scope of the appended claims 35 without departing from the spirit or sacrificing any of the advantages of the invention.

Two of the many possible embodiments 40 of the invention are illustrated in the accompanying drawings, in which:—

Figure 1 is a side elevation, partly in section, of a crutch constructed in accordance with the present invention; Fig. 2 is a section taken on line 2—2 of Fig. 1, on a 45 larger scale; Fig. 3 is a perspective view, on a larger scale, of the lower portion of the crutch; Fig. 4 is a side elevation, partly in section, of the upper portion of a modified crutch; and Fig. 5 is a section taken on line 50 5—5 of Fig. 4, on a larger scale.

Referring now first to Figs. 1 to 3 inclusive, the numeral 10 indicates the staff of the crutch, made of three sections, indicated at 11, 12, and 13. The section 11 comprises 55 two side bars 14, which are united midway by a grip 15, their lower portions being bent

into abutment with each other, as shown at 16. The lower portion of the staff section 11 is of quadrangular cross-section, and is provided with a longitudinal slot 17. This 60 quadrangular portion of the staff section 11 extends into a bore 18 in the upper portion of the staff section 12, and is united with the latter by a headed bolt 19, that is carried by the section 12 and extends through 65 the slot 17 in the section 11. With the bolt coöperates a wing nut 20, serving to clamp, in coöperation with the said bolt, the sections 11 and 12 of the staff together. Through the lower portion of the section 12 70 extends a bore 21, in which is disposed a spring 22, one end of which bears against the staff section 12 and its other end against the head 23 of the staff section 13. This head is 75 slidably disposed in the bore 21, and is held therein by a cap 24, that is provided with interior screw threads 25, meshing with threads 26 on the lower portion of the staff section 12. The staff section 13 extends 80 through the said cap.

The upper ends of the sides 14 of the staff section 11 are fork-shaped, as clearly shown at 27, and straddle the lower reduced part of the head piece 28 of the crutch. This head piece is provided with an arc-shaped slot 85 29, through which extend screw bolts 30, carried by the fork-shaped ends of the side pieces 14, and in engagement with wing nuts 31.

The operation of this device is as follows:—The length of the crutch may be adjusted by loosening the wing nut 20, and moving the sections 11 and 12 toward or away from each other, as required. When 95 in the proper positions, the wing nut is screwed to clamping position, whereby the two sections are firmly held together at the required length.

By loosening the wing nuts 31, the head 28 may be shifted and its angular position 100 in relation to the longitudinal axis of the crutch staff varied, to fit properly under the arm-pit of the user. By screwing up the wing nuts 31, the parts are held against movement.

Inasmuch as the staff section 13 is adapted to telescope into the staff section 12 and by reason of the spring 22 being interposed, the staff is rendered resilient to prevent shocks and jars to the user.

The modification shown in Figs. 4 and 5 of the drawings differs from the one above

described in that its sides 14 are each made of two pieces 32 and 33. The pieces 33 are seated in recesses 34 in the pieces 32, and are each provided with a longitudinal slot 35. 5 Through these slots extend bolts 36, in engagement with wing nuts 37. In this manner the length of the crutch may be adjusted.

Obviously, in the device shown in Figs. 4 and 5 of the drawings the staff section 12 is 10 missing, and the section 13 extends into section 11.

What I claim is:

1. A crutch, comprising a staff having side bars provided with fork-shaped upper 15 ends, a head having a reduced portion seated in said fork-shaped ends and provided with an arc-shaped slot, and screw bolts carried by said fork-shaped ends and extending through said slot.

20 2. A crutch staff, including a section

formed of side bars bent at their lower ends to abut against each other, the abutting portions of said bars being of quadrangular cross-section, and a second section having a bore into which the lower ends of said side 25 bars slidably extend, and means for adjustably securing together said two sections.

3. A crutch staff, including a section provided with a bore, a second section having a head adapted to telescope into said first 30 named section, a spring within said bore interposed between said two sections, and a cap bearing against said first named section and against the head of said second section for preventing dis-engagement of said two 35 sections.

Signed at New York, in the county of New York, and State of New York, this 24th day of Oct., A. D. 1917.

ULRICH KORNSTEIN.
